ATTORNEY-

UNITED STATES PATENT OFFICE.

WILLIAM N. CRANWELL, OF BALTIMORE, MARYLAND, ASSIGNOR OF TWO-THIRDS TO ROBERT H. WRIGHT AND GEORGE O. GILLINGHAM, OF SAME PLACE.

DESIGN FOR A GARMENT-SUPPORTER.

SPECIFICATION forming part of Design No. 27,135, dated June 1, 1897.

Application filed April 13, 1897. Serial No. 682,029. Term of patent 14 years.

To all whom it may concern:

Be it known that I, WILLIAM N. CRANWELL, a citizen of the United States, residing at Baltimore, in the State of Maryland, have invented and produced a new and original Design for Garment-Supporters, of which the following is a specification.

Figure 1 is an obverse perspective view of the design for my belt-hook garment-supporter. Fig. 2 is a reverse perspective view of the same.

A curved plate *a* has on its outer or convex-curved side a long-lipped hook *b*, which projects downward from the upper edge of the plate. The shank *c*, which connects the lip to the plate, is curved to correspond with the curvature of the plate and is shorter than the lip, thereby leaving the rounded ends *b'* of the lip projecting toward the ends of the plate.

On the inner or concave-curved side of the

plate are hooks *d*, whose sharp points project upward.

I claim—

The design for a garment-supporter consisting of a curved plate having on its convex-curved side a long-lipped downward-projecting hook connected to the upper edge of the plate by a shank which curves correspondingly with the said plate and is shorter than the lip leaving the ends of the lip projecting laterally, and the concave-curved side of the plate having upward-projecting hook-points, as herein shown and described.

In testimony whereof I affix my signature in the presence of two witnesses.

WILLIAM N. CRANWELL.
